MEDAL

George E. F. Saum, Chicago, Ill.

Application October 2, 1948, Serial No. 148,942

Term of patent 14 years

(Cl. D29—3)

To all whom it may concern:

Be it known that I, George E. F. Saum, a citizen of the United States, residing at Chicago, in the county of Cook and State of Illinois, have invented a new, original, and ornamental Design for a Medal, of which the following is a specification, reference being had to the accompanying drawing, forming part thereof.

I claim:

The ornamental design for a medal, substantially as shown.

GEORGE E. F. SAUM.
